UNITED STATES PATENT OFFICE

105,074

DESIGN FOR AN ELECTROTHERMO BATH CABINET

Ira M. Petersime, Gettysburg, Ohio, assignor to
The Petersime Incubator Company, Gettys-
burg, Ohio, a corporation of Ohio

Application September 22, 1936, Serial No. 64,960

Term of patent 7 years

To all whom it may concern.

Be it known that I, Ira M. Petersime, a citizen of the United States, residing at Gettysburg, in the county of Darke and State of Ohio, have invented a new, original, and ornamental Design for an Electro-Thermo Bath Cabinet, of which the following is a specification, reference being had to the accompanying drawing forming a part thereof.

In the drawing:

The figure shown is a perspective view of an electro-thermo bath cabinet, showing my new design. Both sides of the cabinet are alike.

I claim:

The ornamental design for an electro-thermo bath cabinet substantially as shown and described.

IRA M. PETERSIME.
